PIEZOELECTRIC DEVICE

Emmanuel Christ Nicholides, New York, N. Y., assignor, by mesne assignments, to Sonotone Corporation, New York, N. Y., a corporation of New York

Application May 24, 1933, Serial No. 672,560

13 Claims. (Cl. 171—327)

This invention relates to piezo-electric devices and it has among its objects improved acoustic devices utilizing vibrators of piezo-electric substances, and particularly of Rochelle salt crystal material.

5 A particular object of the present invention is an improved bone-conduction hearing-aid device utilizing a piezo-electric vibrator for imparting mechanical sound-frequency vibrations to the bone structure of a person of impaired hearing and inducing sounds in his auditory center.

The foregoing and other objects of my invention will be best understood from the following description of exemplifications thereof, reference 10 being had to the accompanying drawings, wherein

Fig. 1 is a perspective view of a Rochelle salt crystal;

Fig. 2 is an elevational view of a Rochelle salt 15 crystal plate;

Fig. 3 is a side view of a bender vibrator unit;

Fig. 4 is an elevational view of the vibrator unit of Fig. 3;

The improvements disclosed herein are a result 55 of efforts to provide a bone vibrator for hard-

of-hearing persons suffering from an impaired outer or middle ear, but having a good inner hearing organ able to hear clearly sound vibrations imparted by conduction over the bones of the head. Since many apparently-deaf persons have 5 this ability to hear well by bone conduction, numerous efforts have been made in the past to devise a hearing-aid device with an electromagnetically actuated bone vibrator for imparting sound-frequency vibrations to the bone structure of the 10 head of such person with sufficient power to induce satisfactory hearing in his auditory center, while keeping the size and shape of the vibrator small, light, and unnoticeable to permit its wear on the head of the user, without calling thereto 15 the attention of bystanders.

Piezo-electric vibrators made of piezo-electric crystal members, such as quartz, tourmaline and Rochelle salt crystals have been known for many years. Such piezo-electric members generate potential differences between different portions thereof when subjected to mechanical deformation, and, conversely, undergo deformations when subjected to electric fields. Rochelle salt crystal members exhibit these piezo-electric effects 20 to a much higher degree than the other similar substances known at present, but are mechanically poorer. I found that if properly used, Rochelle salt crystal material is best adapted for 25 hearing-aid bone vibrators and, in general, for audio frequency vibrators. The growth of Rochelle salt crystals from which satisfactory vibrators may be made is described in the article of R. W. Moore in the Journal of American Chemical Society of 1919, page 1060, and the literature 30 there cited, and is well established. The broad features of my present invention are, however, not limited to Rochelle salt crystal vibrators, 35 but are applicable to other substances exhibiting similar properties.

In Fig. 1 is shown in perspective view a full grown clear Rochelle salt crystal. Such crystal has three principal axes, the optical axis Z extending longitudinally parallel to the direction of the main faces of the crystal, the electric axis 45 X which lies in the direction in which an electric field produces the maximum deformation, and the transverse axis Y which forms with the optical axis Z a plane perpendicular to the electrical axis X. This nomenclature follows that 50 suggested by W. G. Cady in the article "Piezo-electric terminology" in the Proceedings of Institute of Radio Engineers, volume 18, page 2136, 1930.

If a rectangular plate 20 as shown in Figs. 1 55

and 2, cut from the crystal in a direction perpendicular to the X axis (designated as "X-cut plate") with its edges in axial directions (designated as "axial X-cut plate") is subjected to an electric field in the direction of the X-axis, the plate undergoes its greatest deformations in the two diametrical directions D₁, D₂ inclined 45° against the optical axis Z and the transverse axis Y, expanding, for instance, along D₁—D₁, and contracting along D₂—D₂, the deformations reversing in character upon reversal of the direction of the electric field. An X-cut Rochelle salt crystal bar 21 having its longitudinal edges cut under an angle of 45° to the Z and Y axes, designated "45° X-cut bar", when subjected to an alternating field in the direction of the X-axis will elongate during one half of each alternation and contract during the other half of each alternation, depending on the reversal of the direction 20 of the electric field across the bar.

By firmly uniting to each other the flat faces of two axial-X-cut crystal plates 20, as indicated in Fig. 3, for instance, by cementing them with shellack or Canada balsam, and applying across each of said plates potentials inducing opposite deformations in the two plates, the elongation of each plate will be restrained by the contraction of the other plate, and vice versa, causing one pair of diametrically opposed corners of the 25 two-layer unit to bend forward of one face while the other pair of corners will be bent in opposite direction forward of the other face, twisting the unit in one direction, the actions reversing upon reversal of the potentials applied to the 30 two plates.

If two 45°-X-cut rectangular crystal plates are similarly united to each other and proper potential is applied across each plate, inducing opposite deformations in the two plates, the elongation 40 of one plate will be restrained by the contraction of the other plate, causing the mid-portions of one pair of opposite edges of the unit to bend forward of one face, and the mid-portions of the other pair of opposite edges of the unit to 45 bend in opposite direction forward of the other face, twisting the two-layer unit, the actions reversing on reversal of the applied potentials. These two crystal vibrator units are designated as "twisters", the first being a "diametrical", the 50 second an "axial twister".

By similarly uniting the faces of two 45°-X-cut bars or strips 21 of crystal, as shown in Fig. 3, and applying across the two bars potentials inducing in one bar expansion, and in the other bar contraction, the restraint exercised by one bar on the other causes the two-layer crystal unit to bend toward one side face or the other depending on the direction of the applied potentials. Such two-layer unit is designated as 60 "bender".

In order to impress an electric field in the direction of the X-axis upon the two plates of a vibrator unit, electrodes in the form of sheets of conducting material, such as tin foil, are attached to the surfaces of the plates, by Canada balsam, for instance, the junction between the electrode and the crystal surface being made very intimate to secure application of substantially the entire available potential to the body 65 of the crystal plate, and absorb as little as possible potential in the junction layer between the electrode and the crystal surface.

To obtain the above described deformations of the two-layer crystal units, a single electric field 70 may be applied to both plates of the unit by

providing electrode sheets only on the outer exposed faces of the unit and connecting the two sheets to the opposite poles of a source of potential. The individual crystal plates must then have opposite orientation, that is, the two plates 5 must be placed in such relation to each other that on application of a common electric field going in the same direction from one plate to the other, the deformations induced in the portions of one plate will be opposed to the deformations induced in the adjacent portion of the other plate. 10

The deformations of the two-layer crystal units may also be produced by applying opposite potentials to the two plates, so that the direction of the field in one plate is opposite to the direction of the field in the other plate, by cementing an additional intermediate electrode sheet at the junction between the internal surfaces of the two plates, to form a common electrode for the two plates. By connecting the two outer electrode 20 sheets to one pole of a source of potential and connecting the intermediate electrode sheet to the other pole of the source, oppositely directed fields will then be produced across the two plates. In this arrangement the adjacent crystal plates 25 must be of the same orientation, that is, the plates must be parallel to each other in their crystal formation to undergo opposite deformations on applying opposite electric fields to the two plates. 30

With a given potential difference, a greater deformation of the two-layer crystal unit is obtained by separately applying to the two crystal plates the full available potential with the intermediate and outer electrode sheets. It is for 35 this reason that in practical applications, vibrator units with an intermediate electrode layer are preferred over constructions in which no intermediate electrode sheet is used.

By applying electric sound-frequency oscillations to the electrode surfaces of a twister or bender unit, bending motions corresponding to the impressed frequency are imparted thereto, the twister unit having a pair of portions bending alternately in directions opposite to the bending 45 of another pair of portions lying in between, resulting in a twisting movement, and the bender bending alternately in opposite directions perpendicular to its faces, its motion being simpler.

Piezo-electric twister and bender units have 50 been found superior to single crystal plates for use as mechanical vibrators because on actuation by oscillatory potentials, they give a greater vibratory motion. Thus, a single piezo-electric crystal plate varies only slightly its length when 55 subjected to an electric field. When such plates are combined into a twister or a bender unit, the restraint exercised by the longitudinal deformation of one plate restrains the opposite deformation of the second plate over its entire surface, 60 imparting to the two-layer crystal unit a bending motion of greater magnitude than the longitudinal motion of the two crystal plates could give otherwise. In the twister and bender a high degree of restraining action is obtained by cementing 65 the entire contact surfaces of the two plates or bars to each other so that the crystal plate or bar which tends to contract opposes throughout its junction surface the expansion of the oppositely induced adjacent crystal plate or bar bringing about a resulting bending movement. A similar bending effect can also be obtained with a single strip by uniting to the surface of a crystal strip, the surface of a metal strip strong enough 70 to resist longitudinal elongation and contraction, 75

to oppose the contraction and expansion of the crystal when an alternating field is applied thereto, thereby forcing the crystal strip to execute a bending movement instead.

5 Where a relatively large bending action is desired with a small available potential, several similar twister or bender units may be united to each other in the same way as the two plates of a twister or bender unit are united to form a 10 unitary structure of four, six, or more crystal layers, preferably with electrode layers between adjacent junction surfaces of the crystal layers and on the outer faces of the outer crystal layers, connected to impart to one half of the crystal 15 layers a deformation opposite to that imparted to the other half of the crystal layers on application of a potential, and thus causing bending of the entire structure. By means of such multiple-layer benders and twisters it is possible to obtain 20 vibratory movements of substantial power with relatively low potentials.

Much more vibratory energy can be imparted with piezo-electric vibrators at high frequencies of several thousand cycles per second than at low 25 audible frequencies, and particularly in the range of low speech frequency of about 500 cycles and less. The operation of a piezo-electric crystal is to a large degree similar to that of a condenser within the range up to its fundamental frequency. 30 Like a condenser, piezo-electric substances have a high impedance at low frequencies, the impedance decreasing with increase in frequency.

Rochelle salt crystal material has a very much greater piezo-electric effect than quartz or other 35 available piezo-electric substances and exhibits a much greater capacity effect at low frequencies than other piezo-electric substances. These characteristics make Rochelle salt crystal material very desirable for construction of vibrators operating in the audio frequency range and particularly in the speech range down to frequencies of about 100 cycles per second.

Rochelle salt crystal material is well suited for use in multi-layer vibrator units because the 40 thin plates are effective in dissipating the heat and permit holding down of the crystal temperature to a value at which its piezo-electric effect remains stable during operation.

In utilizing twisters and benders for sound 45 production, for instance, by imparting therewith a vibratory movement to the diaphragm of a loud speaker, as practiced heretofore, a relatively large vibrator unit was clamped with one end or edge to a heavy support to hold it firmly in place, the 50 other end or edge being left free to vibrate and to transmit its vibratory energy to the loud speaker diaphragm by coupling the diaphragm to the vibrating free end or edge of the vibrator unit. Relatively large crystal vibrator units were 55 used in such crystal drives, the mass of the crystal being large enough to have a substantial reactive inertia assisting the inertia of the heavy support of the vibrator unit in imparting the vibratory energy to the diaphragm, or other vibration reducing load.

Heretofore, most of the bone vibrators proposed for bone-conduction hearing-aids were of the electromagnetic type requiring a relatively complicated, large-size and heavy mechanisms. My 60 efforts have been directed to the production of a small, light and simple hearing-aid bone vibrator by the use of a Rochelle salt crystal vibrator for converting the sound-frequency oscillations supplied to the vibrator into mechanical vibrations 65 imparted to the bone structure.

Because of the requirement that such vibrator unit shall be small to permit its inconspicuous wear on the head of the impaired person, I constructed for this purpose a small bender of Rochelle salt crystal as shown in Figs. 3 to 5. 5 The bender consists of two Rochelle salt crystal strips 22, 23, each $1\frac{1}{2}$ " long, $\frac{3}{8}$ " wide, and $\frac{1}{16}$ " thick, cemented to each other along their inner faces into a two-layer unit 24, with a pair of tin foil electrode sheets 25, 26 secured to their outer 10 faces and an intermediate electrode sheet 27 secured to the junction surfaces of the two crystal strips and common to the inner faces of the two strips. The lower end of the crystal unit 24 is clamped in a clamp 28 of a rigid insulating material, such as bakelite, in which are imbedded two heavy metallic clamping blocks 29 and 30 separated from each other by an insulating barrier 31 to permit maintenance of a potential difference between the two blocks. In a cavity 32 15 of the clamp, the lower flat end of the crystal unit is clamped between two thin layers 33 of yieldable insulating material, like fibre or mica, by means of a relatively rigid clamping plate 34 of insulating material, such as fibre, held down 20 under pressure by bolts 35 screwed into the projecting sides of the metallic blocks 29 and 30. The electrode sheet 22 on the front surface of the crystal unit and the electrode sheet 23 on the rear side of the crystal unit have resilient 25 contact strips 36 and 37 pressed into contact with block 29, and the intermediate contact sheet 27 has a resilient contact strip 38 pressed against the block 30 within the lateral spaces of the cavity 32, thereby establishing terminal connections 30 from blocks 29, 30 to the outer electrode sheets 25, 26 and the intermediate electrode sheet 27, respectively. To supply electrical oscillations to the electrode sheets, longitudinal sleeve-like holes 40 are drilled into the clamping members 29 and 30 to receive plug pins 42 inserted from the bottom, these plug pins being connected to an insulated two-conductor cord 43 leading to a source of electric sound-frequency oscillations. The weight of the crystal unit 24 without the clamp is 45 about 3 grams, the weight of the clamp is about 15 grams, giving the assembled vibrator unit a support of substantial inertia, which is, however, relatively small compared with the inertia of the mass of the bone structure of the head of the 50 person to which vibratory energy is to be applied with the vibrator unit.

This crystal vibrator unit was tested by connecting its terminal pins 42 to the output terminals of radio and phonograph amplifiers and holding its free end against the mastoid bone either with the hand, or by means of a head band, and also by holding its free end against a loud speaker cone diaphragm. The vibrator unit transmitted satisfactorily high frequency 55 vibrations and high musical notes, but its transmission of low frequency vibrations of the speech range and the low frequency musical range was very poor. Its output was not satisfactory for the intended use as a hearing-aid bone vibrator 60 which requires reproduction of enough low frequency vibrations to make speech well understood by the listener.

I found that these difficulties of transmitting low frequency vibrations can be overcome by 65 shifting the coupling point of the lead to which the vibrations are to be transmitted, from the free end of the vibrator towards the point where the vibrator unit was clamped, near the nodal portion thereof. By holding the free end of the 70 75

vibrator unit having maximum motion against the loud speaker cone and shifting this coupling point nearer to the clamp 28, the amount of the low frequency vibration imparted to the cone gradually increased until at a coupling point near the clamp, the cone would transmit an abundance of low frequency sound. The same experience was obtained by shifting a contact button attached to the vibrator unit and applied to the 10 mastoid bone from a point near the end of the vibrator area toward the clamp, the sound gaining in low frequency tones and the speech becoming clearer as the button was brought nearer to the clamp.

15 I have also found that additional improvement of the transmission of low frequencies may be obtained by attaching a weight to the vibrating portion of the crystal unit. Attaching of a weight to the vibrating crystal bar has also a 20 very pronounced effect in increasing the amount of low frequency oscillation energy transmitted from the crystal bar to the cone or to the bone structure. By combining the use of an additional weight attached to the vibrating crystal bar with a coupling connection lying near the clamp of the vibrator, there is obtained a cumulative increase of the amount of low frequency sound imparted by the crystal unit to the cone or to the bone structure, each effect contributing 25 a share in improving the richness of the output in low frequency vibrations.

The foregoing improvements in the operation of vibrator units enables the construction of small bone vibrators suitable for inconspicuous wear by persons of impaired hearing and yet able to produce and impart to the bone structure of a person of impaired hearing sufficient vibrations of the low frequency sound range to properly reproduce speech, and enough of the high 40 frequency range to secure good reproduction of music. Such bone vibrator unit for a portable hearing-aid device embodying the foregoing improvements is shown in enlarged scale in Figs. 6 to 8 of the drawings.

45 The bone vibrator comprises a small flat longitudinal casing 59 closed on one side by a wall 51 and having an opening 52 on the other side. The casing is made of an insulating molded substance, such as bakelite, and has imbedded in its lower 50 part a pair of heavy metallic clamps 53, 54, insulated from each other by the body of the casing, like in the clamp shown in Figs. 3 to 5. Into a cavity provided between the two metal blocks 53 and 54 there is clamped between fibre layers 55 55 the lower flat end of a two-layer Rochelle salt crystal bender unit 56 by means of an insulating clamping block 57, the several elements being constructed and arranged like the elements shown in Figs. 3 to 5. The outer electrode sheets 59, 60 are connected by contact strips 61, 62 with the metallic block 53, and the intermediate electrode sheet 63 is connected by a contact strip 64 with the metallic block 54, the metallic blocks having perforations 65 and 66 for receiving plug pins 67 of a cord 68 leading to the source of sound-frequency electric oscillations.

A short distance above the clamped lower end portion, the crystal unit 56 has clamped thereto a button clamp 70 having two members 71, 72 70 and intermediate yieldable layers 73 embracing the vibrating unit and held together by screws 74.

The front side of the button clamp 72 holds a bolt 76 over which is screwed a contact button 75 77 projecting through an opening 78 in the casing

wall 51 and movable within a collar 79, of rubber or similar material, lining the opening 78 of the casing. The amount of the projection of the button 77 beyond the casing wall 51 may be adjusted by interposition of one or more washers 80 between the button and the clamp member 72.

To the free top end of the crystal vibrator unit 56 is secured a weight 84 of lead, for instance, having in the interior a cavity 85 with a narrow portion fitting over and attached, as by cementing, to the flat sides of the upper end of the crystal vibrator unit 56, and a downward skirt-like extension for holding additional weight without clamping too much of the surface of the crystal, and without increasing the length of the unit. An insulating layer 86 may be interposed at the 15 crystal surface holding the weight to prevent direct contact with the weight surface, a free space 87 being left at the top side of the crystal 20 unit.

The space within the casing 50 is large enough to permit free bending movement of the projecting portion of the crystal unit 56 with its button clamp 77 and its weight 84 when vibrating in the direction perpendicular to its faces as indicated by the arrows 88 in Fig. 6, sufficient spaces being left on both sides of the weight 84 to permit the crystal unit to reach its maximum amplitude without touching the walls of the 25 casing.

The rear wall of the casing is enclosed by a cover sheet 90 which has clamped thereover a second sheet 91 provided with a channel 92 for receiving the flat end of a grip portion 93 attached to a head band 94 for applying the button 35 77 with pressure to the mastoid bone of a person using the instrument as shown in Fig. 9. The cover 90 and the channel sheet 91 may be firmly clamped in place by screws 95 engaging the edge of the casing wall. The conductor cord 68 carrying the conductors has its contact pins attached to the terminal blocks 53 and 54 of the 40 vibrator unit, the cord being easily hidden in the clothing of the user.

The vibrator may be connected to the output 45 circuit of an amplifier, of a radio or phonograph instrument, or it may have its own sound oscillation transmitting apparatus as shown in Fig. 10. This apparatus comprises a transmitting microphone 96 connected through a cord 97 with the 50 input circuit of an amplifying device 98 to produce current oscillations from the battery 99 in accordance with the sound vibrations impinging on the diaphragm of the transmitting microphone 96. The produced oscillations are amplified in 55 the amplifier 98 and delivered through an adjustable resistor 100 to a transformer 101 from where the amplified and suitably transformed oscillations having a potential required for actuation of the crystal vibrator unit 56 are impressed upon 60 the electrode layers of the vibrator unit 56 held with the button 77 against the mastoid bone or other suitable portion of the bone structure of the head of the person. The small crystal vibrator unit constructed and arranged as described 65 above will operate satisfactorily with a source applying a voltage of about 10 volts to the crystal strips.

Where the available operating voltage is low, the vibrator unit is preferably made with four 70 layers of crystals, each layer pair being connected in parallel with the other, so that the several layer pairs work in unison and vibrate like a single unit. In using such four-layer vibrator unit, the length and the width of the individual 75

crystal strips may remain of about the same dimensions as described in connection with the vibrator of Figs. 3 and 4, the thickness of the individual strips being reduced about one half 5 so that the complete vibrator unit has about the same dimensions as the two-layer vibrator unit for a hearing-aid vibrator described above.

A completely assembled bone vibrator as shown in Figs. 6 to 8 is about 1 $\frac{3}{4}$ " long, $\frac{3}{4}$ " wide, and 10 $\frac{3}{8}$ " thick, being small and suitable for inconspicuous wear back of the ear of the user, with the button held under slight pressure against the mastoid bone to permit transmission of vibrations from the vibrator arm in the interior 15 to the bone structure. This pressure does not materially displace the vibrating unit inside the casing from its neutral position and does not disturb its free vibrations. The weight of the crystal portions of the vibrator is about 2 $\frac{1}{2}$ grams, the 20 weight of the additional weight attached to the vibrator bar is about 3 $\frac{1}{2}$ grams, and the total vibrator with the casing weighs about 18 grams, being thus light and pleasant to wear.

Upon excitation of the electrode sheets with 25 electric sound-frequency oscillations of about 10 volts produced by speech or music, the piezo-electric forces impart to the projecting crystal bar a vigorous vibratory bending action causing the weighted end of the bar to vibrate with a substantial amplitude, the amplitude of the vibrations decreasing in the direction toward the clamped nodal portion of the bar. The contact button carried by the lower portion of the bar is thus actuated by the vibration of the portion 30 of the bar on which it is held, and imparts to the bone structure, with which its outer surface is in contact, vibratory energy corresponding to the vibrations of the crystal bar. The coupling of the bone structure to a point of the vibrating 35 crystal bar relatively remote from its free end, and disposed near to the nodal region, secures a better match between the impedance of the bone structure and the impedance of the part of the bar coupled to the bone structure for low frequency vibrations than could be obtained by 40 coupling the bone structure to the end portion of the vibrating crystal bar. By locating the button at a portion of the bar at which the most effective impedance match for low frequency vibrations is obtained between the bone structure and the vibrator unit, an optimum condition of 45 energy transfer from the bar to the bone structure is obtained, enabling imparting of sufficient vibratory energy, including ample low frequency energy, to secure good reproduction of sounds 50 of the speech and musical range. The transfer of low frequency vibrations is further increased by the additional weight attached to the crystal vibrator bar, materially supplementing the 55 proved ability of the vibrator unit to impart low frequency vibrations to the bone structure.

The advantageous features of coupling the load 60 that is to be vibrated to a portion of the vibrating crystal unit having a smaller vibrating amplitude than the vibrating end portions of the vibrator unit, and the weighting of the vibrating portion part of the piezo-electric crystal vibrator unit are of great practical importance not only in 65 order to enable construction of miniature vibrator devices capable of imparting sufficient low frequency vibrations, such as are required in connection with bone-conduction hearing-aids, but are also of great advantage in other fields using 70 piezo-electric vibrators for driving loud speaker 75

diaphragms, telephones, phonograph recorders, and like devices.

In Fig. 11 is shown a loud speaker driven by a piezo-electric vibrator unit and arranged in accordance with the broad principles of the invention described above. It comprises a heavy vibrator housing 110 held on the top of a heavy conical base 111. The front wall of the casing has a circular opening 112 over which is attached the flange 113 of a cone bracket 114 carrying on 10 a circular rim 115 the forward end 116 of a cone diaphragm 117 by means of a flexible annular fabric strip 118 permitting forward and backward movement of the cone during vibrations. Within the casing 110 back of the opening 112 is 15 mounted a vibrator unit 120 in the form of a bender of Rochelle salt crystal material constructed like the bender shown in Figs. 3 to 5, but considerably larger in size. It may, for instance, comprise two crystal bars 121 and 122, 20 each about 5" long, 1 $\frac{1}{2}$ " wide, and $\frac{1}{8}$ " thick assembled with two outer electrode sheets 123 and an intermediate electrode sheet 124, and clamped at the lower end within a clamp 125 constructed like the smaller clamp of Figs. 3 to 5. 25 The clamp 125 is attached to the bottom wall 126 of the casing by bolts 127, or in some other suitable way, so that the weight of the clamp 125 and the weight of the casing attached to it act as a heavy mass definitely fixing in space the 30 clamped lower end of the bender unit 120. A weight 128 is attached to the upper end of the bender unit 120, being constructed like the corresponding weight 84 of the bender of Figs. 6 and 7. A coupling clamp 129 similar to the button 35 clamp 70 is attached to a portion of the upwardly projecting bender unit 120 at a point lying a small distance above the clamp 125 at which a good impedance match is obtained with cone for transfer of low frequency sound vibrations. A coupling 40 rod 130 extending from the coupling clamp 129 is attached to the center of the cone 117 and couples the cone to the bender.

Electrical oscillations are supplied to the bender by connecting the electrode sheets 123 and 124 45 thereof, like in the arrangement shown in Figs. 3 to 5, to leads 131 extending from an electric sound-frequency oscillation source, such as the output circuit of an audio frequency amplifier. By coupling the cone to an intermediate point 50 of the crystal vibrator bar and the addition of weight to it, a much smaller vibrator unit than required in the prior art constructions will produce in such speaker a large output rich in low frequency vibrations and securing natural reproduction of speech and music. 55

In Figs. 12 and 13 is shown a phonograph recorder head made in accordance with my invention. At the end of a horizontally mounted recording arm 140, carrying in its interior the 60 conductor leads 141 from a source of sound-frequency oscillations, is provided a clamping member 142 to which the flat end portion of a Rochelle salt crystal bender bar 143 is clamped by a clamping plate 144, like in Figs. 3 to 5. 65 The free end of the bender bar has attached thereto a weight 145 and the bender is set into horizontal vibratory bending movement by supplying oscillation to its electrode sheets. At an intermediate point of the bender bar, not far 70 from the clamp 144, there is provided a coupling clamp 146 similar to the coupling clamp 70 and 129 of Figs. 8 and 11. One of the clamping members has on its lower side a mounting for receiving and clamping a stylus carrier 148 to cut 75

a groove in a phonograph recording disc 149. A housing 150 in the form of a tube with an opening 151 for permitting downward projection of the stylus 148 encloses the bender unit. In 5 operation, the record disc 149 is rotated and the sound-frequency oscillations are impressed upon the bender crystal by means of the leads 141, imparting to the bender a vibratory motion. By using a weight 145 on the end of the vibrator 10 and coupling the stylus 148 to an intermediate portion of the crystal bar having a good impedance match with the cutting stylus load 148, the bender imparts to the cutting stylus 148 a much larger amount of low frequency energy than 15 possible otherwise, enabling the construction of small record cutters capable of cutting records of low frequency sounds.

In Fig. 14 is shown a telephone receiver having a diaphragm 153 for reproducing sound and 20 driven by a Rochelle salt crystal bender 154 in accordance with my invention. The diaphragm 153 may be in the form of a circular thin metal sheet held at its edges between two washers 155 which are clamped to a shoulder 157 of an enclosing casing 158 by an inward projection 159 of the cover 160. The bender 154 is made of two crystal strips 162, 163 united to each other and clamped at the lower end by a clamp 164 like the bender of Figs. 3 to 5. The bender unit 25 may be very small, for instance, about $\frac{3}{4}$ " long, $\frac{1}{4}$ " wide, and $\frac{1}{16}$ " thick. The clamp 164 is attached to a heavy metal plate 165, that is secured to the telephone casing by means of screws 167. The bender has attached to its free end a 30 weight 168, and at its intermediate portion it has attached to it a coupling clamp 169 which is connected to the center of the diaphragm 153 by a coupling rod 170, the several elements being constructed similar to the loud speaker of Fig. 11. 35 By impressing oscillatory sound-frequency electric oscillations on the crystal electrodes through conductors of a cord 171 connected to the electrode sheets as described before, the little bender 154 is set into vibration to vibrate in accordance 40 with the impressed oscillations. By reason of the coupling of the diaphragm to an intermediate point of the bender bar, the impedance of which is well matched to the impedance of the diaphragm, and the weighting of the vibrating crystal bar, this small and simple vibrating structure will readily supply enough low frequency vibratory energy as well as sufficient high frequency energy to secure good reproduction of 45 speech and music.

The improved utilization of piezo-electric vibrator units by matched coupling to the vibrating piezo-electric member and by weighting the member is not confined to bender type vibrators, but is applicable to other types of piezo-electric 50 vibrating units. In Figs. 15 and 16 there is shown a loud speaker cone driven by an axial twister unit in accordance with my invention. A twister unit 175, made of two rectangular crystal plates 176, 177 cut from a Rochelle salt crystal like the plate 20 of Figs. 1 and 2, and united to each other, is provided with exterior electrode sheets 178 and an intermediate electrode sheet 179 at their junction surface, as described before. The crystal unit may measure, for instance, 55 $4\frac{1}{2}$ " x $4\frac{1}{2}$ " x $\frac{3}{16}$ ". One corner 180 of the crystal unit has its edges clamped between a heavy supporting member of metal 181 and a clamping block 182 engaging the edges of the corner of the crystal unit for a substantial length to fix the 60 position of the corner portion in the space and

prevent its vibration when excited by potentials applied to the electrode sheets. To secure uniform compression of the clamped portion of the crystal, strips 183 of yieldable insulating material are interposed at the clamping surfaces. The 5 unclamped portion of the twister unit projects upwardly, and weights 185 are attached to the three corners thereof in a way similar to the weight attached to the end of the bender unit 56 of Figs. 6 and 7. The supporting clamping 10 member 181 is provided at its bottom with a heavy base plate 187 which is secured by bolts 188 to the bottom side 189 of a casing 190 enclosing the vibrator unit. Cords 191 imbedded in channels within the supporting member 181 15 provide insulated connections to the pair of outer electrode sheets 178 and the intermediate electrode sheets 179, respectively, to permit excitation of the crystal plates of the twister.

Like in Fig. 11, the casing 190 has an opening 20 193 against which is mounted a flange 194 of a cone bracket 195 supporting the front edge of cone 196.

To transmit the vibrations from the twister unit 175 to the cone 196, there is provided a 25 clamping frame 197, shown in cross section in Fig. 17, comprising a pair of bars 198 held on opposite sides of the twister by spacers 199 and secured to each other by bolts 200, the bars 198 carrying at their center clamping blocks 201 engaging from opposite sides an intermediate portion of the twister 202, with intermediate resilient layers 203 of fibre, for instance, serving to uniformly distribute the pressure of the clamping blocks over the crystal surface. The front 30 bar of the clamping frame 197 has mounted thereon a coupling rod 204, the other end of which is adjustably attached to the center of the cone 196.

To operate the loud speaker, sound-frequency oscillations from an audio frequency amplifier 40 are impressed through cords 191 on the electrode sheets 178 and 179 of the two crystal plates. Because of the clamping of one corner portion of the twister, a strong vibratory bending movement 45 is imparted to the upwardly projecting portion 210 of the twister lying opposite the clamped corner and, to a lesser degree, to the two lateral corners 211 of the twister. Through the use of the weights attached to the three vibrating corners 210 and 211, the twister vibrates with a substantial amount of low frequency vibrations which it would not have without the additional weights. By coupling the cone to a point of the twister lying at a distance from the freely vibrating end 50 portion of the crystal plates, and near to the nodal portions, the impedance of the cone may be matched to a good degree with the impedance of the effective twister portion to secure a higher transfer of low frequency vibrations to the cone 55 and production of more low frequency sound vibrations by the cone than would be possible if the outer vibrating edges of the twister plate were used for coupling the twister to the cone.

Another application of the principles of the 60 present invention in connection with a twister drive is shown in Figs. 18 and 19 in connection with a phonograph record cutter. At the end of a horizontally mounted cutter arm 220 is provided a relatively heavy supporting member 221 against 65 which a twister unit 222 similar to that described in connection with Figs. 15 and 16, but smaller in size, is clamped along the two edges of one of its corners by means of a clamping plate 223 secured to the clamping support by screws 224, resilient 70

5 layers 225, of fibre or rubber, being interposed at the clamping surfaces. The electrode sheets 226 and 227 of opposite polarity are connected to a pair of conductor leads 228, leading through a hollow channel in the supporting member 220 to a sound frequency source of electric sound-frequency oscillations for imparting a vibratory bending movement to the unclamped exposed portion of the twister, the biggest amplitude of the 10 twister being at the corner portion 229 opposite the clamped corner portion thereof. By attaching a weight 230 of lead or the like, as described before, to the corner 229 of the twister, its vibrations are increased in the low frequency range.

10 15 A coupling frame 231 made similar to the coupling frame 197 has two of its contact members 232 clamped through intermediate flexible layers to an intermediate portion 233 of the twister between its free vibrating corner 229 and its 20 clamped corner, the clamping frame carrying on two rigid arms 234 a cutter mounting 235 to which a cutter 236 acting on a record 237 may be secured. The clamping frame may be additionally supported by two resilient strips 238 which 25 are attached at their ends to the twister clamp 221 and to the clamping frame 231 and arranged to permit lateral vibration of the frame 231 when actuated by the vibration of the twister through the clamping contacts 232.

30 Upon energization of the electrode sheets 226 and 227 of the twister 222 from a source of electrical sound-frequency oscillations through the lead 228, a vibratory motion having an abundance of low frequency vibrations will be imparted to the twister plate by the action of the weighted corner 229 of the twister unit, and by matched coupling of the cutter head to an intermediate portion of the vibrating twister unit will be secured effective transmission of the low frequency 35 40 vibrations from the twister unit to the cutter enabling the cutter to produce a record that will give good reproduction of the low frequency range of speech and music.

The invention described in connection with the 45 exemplifications described above enable utilization of piezo-electric crystal vibrators to produce and deliver substantial amounts of low frequency vibratory energy to sound producing devices in a much simpler way and to a much greater extent than heretofore thought possible. This is achieved by coupling the load to which the vibrations are to be imparted to a portion of the vibrating crystal unit that matches the impedance of the load to a much larger extent than the portions of the vibrator having the maximum vibration amplitude, and by adding weight to the vibrating portions of the vibrating crystal unit which causes an increase of the low frequency 50 55 vibration output of the vibrating unit, compared to its output when it vibrates under the same conditions without the additional weight, and to a still greater degree by the combined use of the two effects.

60 The principles underlying my invention are not limited to the particular exemplifications or the details referred to in connection with the description of the exemplifications thereof, and many modifications thereof will suggest themselves to those skilled in the art. It is accordingly desired that the appended claims be given a broad construction commensurate with the scope of the invention.

I claim:

75 1. In a piezo-electric vibrator device for sup-

plying mechanical vibratory energy to a vibratory load comprising a vibrator member of piezo-electric substance having a nodal portion undergoing negligible movement during vibration, electrode means for impressing an electric oscillatory field on said substance for imparting to said vibrator member a vibratory motion relative to a portion thereof, means actuated by a portion of reduced amplitude on said member lying intermediate a nodal portion and the portion of maximum 10 amplitude thereof for imparting vibratory energy from said member to a vibratory load, and a weight of a substance of greater specific weight than said piezo-electric substance attached to the vibrating portion of said member. 15

2. In a piezo-electric vibrator device for supplying vibratory energy to a vibratory load, a vibrator member of piezo-electric substance having a nodal portion undergoing negligible movement during vibration, electrode means for impressing an electric oscillatory field on said substance for imparting to said vibrator member a vibratory motion relative to a portion thereof, means for coupling to a vibratory load an intermediate portion of said vibrator member lying 20 closer to the nodal portion than the portion of maximum amplitude of said member, and a weight greater than the weight of the piezo-electric substance of said member attached to the vibrating portion of said member having 25 greatest amplitude. 30

3. In a piezo-electric vibrator device, one or more pairs of layers of piezo-electric crystal substance united to each other along their faces to constitute an integral crystal unit, electrode layers in contact with the faces of said crystal layers for impressing oscillatory electric fields across a pair of layers alternately inducing in each layer an expanding force restrained by a contracting force induced in the adjacent layer imparting to the unit a vibratory bending movement, means confining a nodal portion of said unit against vibratory movement, means mechanically coupled to an intermediate vibrating portion 35 of said crystal unit lying closer to said nodal portion than the portions of maximum amplitude of said unit to derive vibratory energy from said unit and impart said energy to an external load, and a weight of a substance of greater 40 specific weight than said piezo-electric substance attached to the vibrating portion of said unit. 45

4. In a piezo-electric vibrator device for supplying vibratory energy to a vibratory load, one or more pairs of layers of piezo-electric Rochelle salt crystal substance united to each other along their faces to constitute an integral crystal unit, electrode layers in contact with the faces of said crystal layers for impressing oscillatory electric fields across a pair of layers 50 alternately inducing in each layer an expanding force restrained by a contracting force induced in the adjacent layer imparting to the unit a vibratory bending movement, means mechanically coupled to an intermediate vibrating portion 55 of said crystal unit lying closer to said nodal portion than the portions of maximum amplitude of said unit to derive vibratory energy from said unit and impart said energy to a load, and a weight of a substance of greater specific weight 60 than said piezo-electric substance attached to the vibrating portion of said unit. 65

5. In a piezo-electric vibrator device, a layer of piezo-electric crystal substance, electrode means for impressing oscillatory electric fields 70 75

- across the thickness of said layer imparting thereto alternating forces tending to longitudinally deform said layer, means restraining said layer against longitudinal deformation and imparting under the action of said forces a vibratory bending movement to said layer relatively to a nodal portion thereof, and a weight of a substance of greater specific weight than said piezo-electric substance and greater weight than about 5 half the weight of said layer attached to the vibrating portion of said crystal layer.
6. In a piezo-electric vibrator device, one or more pairs of layers of piezo-electric crystal substance united to each other along their faces to 10 constitute an integral crystal unit, electrode layers in contact with the faces of said crystal layers for impressing oscillatory electric fields across a pair of crystal layers inducing alternately in each of said layers opposite mutually restraining forces imparting to said unit a vibratory movement, and a weight greater than the weight of the piezo-electric substance of said unit attached to the vibrating portion of said unit.
- 15 7. In a piezo-electric vibrator device, one or more pairs of bars of piezo-electric crystal substance united to each other along their faces to constitute an integral crystal unit, electrode layers in contact with the faces of said crystal bars for impressing oscillatory electric fields across a pair of bars alternately inducing in each bar an expanding force restrained by a contracting force induced in the adjacent bar imparting to the unit a vibratory bending movement, and a weight of a substance of greater specific weight than said piezo-electric substance having a weight greater than half the weight of said substance attached to the vibrating portion of said unit.
- 20 8. In a piezo-electric device for imparting mechanical vibrations to a load, a vibrator comprising a member of piezo-electric substance, supporting means restraining one part of said vibrator and supporting another part of said vibrator of substantial mass in a floating vibrating condition, electrode means for impressing electrical oscillations of said substance to produce a vibratory motion between the restrained and the floating parts of said vibrator, and coupling means 25 for coupling an intermediate portion of said vibrator disposed between the restrained and floating parts of the vibrator to a load, the floating parts of the vibrator extending beyond said coupling portion having a substantial mass for producing by the vibratory action of its mass forces transmitting vibratory energy to said load.
- 25 9. In a piezo-electric device for imparting mechanical vibrations to a load, a vibrator comprising a member of piezo-electric substance, supporting means restraining one part of said vibrator and supporting another part of said vibrator in a floating condition, electrode means for impressing electrical oscillations of said substance to produce a vibratory motion between the restrained and the floating parts of said vibrator, and means for coupling an intermediate portion of said vibrator disposed between the restrained and floating parts of the vibrator to a load, the floating part of the vibrator extending beyond said coupling portion having a substantial mass for producing by the vibratory action of its mass forces transmitting vibratory energy to said load.
- 30 10. In a piezo-electric device for imparting mechanical vibrations to a load, a vibrator comprising a layer of piezo-electric substance, supporting means restraining one part of said vibrator and supporting another part of said vibrator in a floating vibrating condition, electrodes for impressing on said layer electric oscillations inducing in said layer longitudinal deformation forces producing a vibratory bending motion between the restrained and floating parts of said vibrator, and coupling means for coupling to a vibratory load an intermediate portion of said vibrator disposed between the restrained and floating parts of the vibrator to a load, the floating part of the vibrator extending beyond said coupling portion having a substantial mass for producing by the vibratory action of its mass forces transmitting vibratory energy to said load.
- 35 11. In a piezo-electric device for imparting mechanical vibrations to a load, a vibrator comprising a layer of piezo-electric substance, supporting means restraining one part of said vibrator and supporting another part of said vibrator in a floating condition, means including electrodes for impressing on said layer electric oscillations inducing in said layer longitudinal deformation forces producing a vibratory bending motion between the restrained and floating parts of said vibrator, and means for coupling an intermediate portion of said vibrator disposed between the restrained and floating parts of the vibrator to a load, the floating part of the vibrator extending beyond said coupling portion having a substantial mass including a body of greater specific weight than said piezo-electric substance for producing forces transmitting vibratory energy to said load.
- 40 12. In a piezo-electric device for imparting mechanical vibrations to a load, a vibrator comprising a member of piezo-electric Rochelle salt crystal substance, supporting means restraining one part of said vibrator and supporting another part of said vibrator in a floating vibrating condition, electrode means for impressing electrical oscillations of said substance to produce a vibratory motion between the restrained and the floating parts of said vibrator, and coupling means for coupling an intermediate portion of said vibrator disposed between the restrained and floating parts of the vibrator to a load, the floating part of the vibrator extending beyond said coupling portion having a substantial mass for producing by the vibratory action of its mass forces transmitting vibratory energy to said load.
- 45 13. In a piezo-electric device for imparting mechanical vibrations to a load, a vibrator comprising a member of piezo-electric Rochelle salt crystal substance, supporting means restraining one part of said vibrator and supporting another part of said vibrator in a floating condition, electrode means for impressing electrical oscillations of said substance to produce a vibratory motion between the restrained and the floating parts of said vibrator, and means for coupling an intermediate portion of said vibrator disposed between the restrained and floating parts of the vibrator to a load, the floating part of the vibrator extending beyond said coupling portion having a substantial mass including a body of greater specific weight than said piezo-electric substance for producing forces transmitting vibratory energy to said load.

EMMANUEL CHRIST NICHOLIDES.
